(57) **CLAIM**

The ornamental design for a sitz bath, as shown and described.

DESCRIPTION

FIG. 1 is a front, right, and top perspective view of a sitz bath, showing my new design;

FIG. 2 is a rear, left, and bottom perspective view thereof;

FIG. 3 is a front view thereof;

FIG. 4 is a rear view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a front, right, and top perspective view showing the sitz bath in a position of use.
The broken lines depict portions of the sitz bath that form no part of the claimed design.

1 Claim, 9 Drawing Sheets
